UNITED STATES PATENT OFFICE.

GUSTAVE A. HENCKEL, OF NEW YORK, N. Y.

DESIGN FOR A BORDER-SECTION.

45,751.

Specification for Design.

Patented May 12, 1914.

Application filed March 18, 1914. Serial No. 825,702. Term of patent 7 years.

To all whom it may concern:

Be it known that I, GUSTAVE A. HENCKEL, a citizen of the United States of America, residing at New York, in the county of New York and State of New York, have invented a new, original, and ornamental Design for a Border-Section, of which the following is a specification, reference being had to the accompanying drawing, forming part thereof.

The figure shows a design for a border section.

I claim:

The ornamental design for a border section, as shown.

In testimony whereof I have signed this specification in the presence of two subscribing witnesses.

GUSTAVE A. HENCKEL.

Witnesses:

H. M. MARBLE,
PAUL H. FRANKE.
